WALL AND CEILING COVERING.

No. 19,603.

Patented Jan. 21, 1890.

UNITED STATES PATENT OFFICE.

CHARLES CONSTANTINE HISCOE, OF NEW YORK, N. Y., ASSIGNOR TO FREDERICK BECK, OF SAME PLACE.

DESIGN FOR A WALL AND CEILING COVERING.

SPECIFICATION forming part of Design No. 19,603, dated January 21, 1890.

Application filed December 26, 1889. Serial No. 336,035. Term of patent 3½ years.

To all whom it may concern:

Be it known that I, CHARLES CONSTANTINE HISCOE, a citizen of Great Britain, residing at New York, in the county of New York and State of New York, have invented and produced a new and original Design for a Wall and Ceiling Covering, of which the following is a specification, reference being had to the accompanying drawing, forming part thereof.

5 The leading feature of my design represents festoons of flowers, figure 1, and floral groups, figure 2, and also waving ribbons, figure 3, apparently held in position by studs, figure 4. The groundwork is decorated with plain buttons, figure 5, and a crepe-like pattern, figure 6.

What I claim is—

A design for a wall and ceiling covering herein shown and described, consisting of festoons of flowers and floral groups with waving ribbons, with a groundwork of plain buttons and a crepe-like pattern.

CHARLES CONSTANTINE HISCOE.
